J. I. MABBETT, OF TITUSVILLE, PENNSYLVANIA.

Letters Patent No. 86,310, dated January 26, 1869.

IMPROVED WEATHER-STRIP FOR DOORS.

The Schedule referred to in these Letters Patent and making part of the same.

To all whom it may concern:

Be it known that I, J. I. MABBETT, of Titusville, in the county of Crawford, and State of Pennsylvania, have invented certain new and useful Improvements in Weather-Strips for Outside Doors; and I do hereby declare that the following is a full, clear, and exact description thereof, reference being had to the accompanying drawings, and to the letters of reference marked thereon, which form a part of this specification, and in which—

Figure 1 represents a front view, and

Figure 2, an inverted view of my weather-strip.

Similar letters indicate like parts in both figures.

My invention relates to improvements in weather-strips, and consists in the employment of a drop, or hinged bar, covered with oil-cloth or rubber, in combination with a spring-bar, or its equivalent, which will hereinafter be fully described.

In the accompanying drawings—

A represents an ordinary door, and

B, the frame of the same.

C, the wooden bar or drop, is covered with oil-cloth or rubber, *a*, and hinged, by means of the cover, to the lower outer end of the door.

The cover *a* is made to project beyond the lower

edge of the drop C, in order to fit water-tight against the frame when the door is closed.

The spring-bar *b* is made as seen in fig. 2, and it may be made of rubber, and is secured to the door under the drop.

d is a pin, secured to the inner surface of the frame B, and is so placed that, when the door is closed, the weather-strip, or drop, C, will be forced against it, and it being made to yield, will thereby be securely held down against the bottom of the door, and the sill of the door-frame, preventing any possible chance of the water gaining admittance to the room.

Having thus fully described my invention,

What I claim as new, and desire to secure by Letters Patent, is—

The oil-cloth or rubber, *a*, hinged to the lower part of the door, and projecting below it, in combination with the drop C, spring-bar *b*, and pin *d*, all arranged and operated as set forth.

In testimony that I claim the foregoing as my own, I affix my signature, in presence of two witnesses.

J. I. MABBETT. [L. s.]
